FIG. 1

FIG. 5

FIG. 4

FIG. 7

FIG. 6

FIG. 1 is a top perspective view of a bathroom module showing my new design, with the interior shower door and the outer front door in a closed position;

FIG. 2 is a fragmentary perspective view thereof, with the interior shower door in a folded position and with the outer door open and the left wall broken away for convenience of illustration;

FIG. 3 is another fragmentary perspective view thereof, with the front wall removed for convenience of illustration;

FIG. 4 is a fragmentary perspective view similar to FIG. 2, with the sink in a partially pivoted position;

FIG. 5 is another fragmentary perspective view similar to FIG. 2, with the sink in operative position;

FIG. 6 is a third fragmentary perspective view similar to FIG. 2, with the interior shower doors in a closed position; and,

FIG. 7 is a fragmentary perspective view thereof, with the rear wall broken away for convenience of illustration and the interior shower doors in a closed position.

I claim:

The ornamental design for a bathroom module, as shown in the accompanying drawings.
